Atty.

UNITED STATES PATENT OFFICE.

FREDERICK GRINNELL, OF PROVIDENCE, RHODE ISLAND.

AUTOMATIC FIRE-EXTINGUISHER.

SPECIFICATION forming part of Letters Patent No. 269,202, dated December 19, 1882.

Application filed February 20, 1882. (No model.)

To all whom it may concern:

Be it known that I, FREDERICK GRINNELL, of the city and county of Providence, and State of Rhode Island, have invented a new and useful Improvement in Automatic Fire-Extinguishers; and I hereby declare that the following is a full, clear, and exact description of the same, reference being had to the accompanying drawings, forming part of this specification.

This invention has reference to an improved device for securing the valve of an automatic fire-extinguisher to its seat, so as to make a tight joint, and also so that when the fusing-point of the solder is reached by the surrounding atmosphere the solder will readily melt and the internal pressure will readily rupture the soldered joint.

The invention consists in the application of compound levers to hold the valve to its seat, as will be more fully set forth hereinafter.

Figure 1 is a sectional view of an automatic fire-extinguisher in which a valve forming a disk much larger than the outlet and provided with a serrated edge is held against the outlet or valve-seat by means of two levers, the end of one of which is secured by solder. Fig. 2 is a view of the same device shown open. Fig. 3 is a sectional view of an automatic fire extinguisher in which the valve is placed under a distributor, and is provided with a long stem, the end of which stem is held by means of compound levers secured by solder. Fig. 4 is a sectional view of a valve placed into a water-main, the end of the valve-stem being held in place against the internal pressure by means of compound levers secured together by a strip of metal secured by solder.

In the drawings, *a a* are the outlets, surrounded by valve-seats, against which the valves *b b* are held, so as to resist the internal pressure. *c c* are levers, one end of which rests in a notch or bolster, *e e*, the center resting against the valve, as shown in Fig. 1, or the valve-stem, as shown in Figs. 3 and 4, the free end of the levers *c c* forming the fulcrum of the levers *d d*, one end of which rests on the notch or bolster *ff*, the free end being secured to the frame *g* by means of a thin metal strip or loop, *h*, to the lever *c* by means of fusible solder. By the use of compound levers a great leverage is secured with short levers, and thereby the levers can be placed within the size of the extinguisher, as is shown in the

drawings. It is obvious that three or even four levers may be used, and so the force may be compounded indefinitely.

In Fig. 1 the lever *d* is shown curved. This brings the soldering-point *i* perpendicular below the center of the valve. The free end of the lever *d*, being thus secured by solder, forms a firm resistance to the internal pressure on the valve, which cannot be ruptured by pressure. As soon, however, as the solder is fused by heat the end will move quickly away from the solder, so that a partial release of the valve is not possible, and the prompt and efficient action of the extinguisher is insured. The lever *c* in Fig. 1 has one side curved, so as to bear on the center of the valve-disk only, thus allowing the valve to seat itself freely on the seat.

Various modifications may be made in the form of the levers, and any desired leverage may be secured by moving the free end of the lever *c* nearer the bearing end *f* of the lever *d*.

K is a coiled spring arranged to assist in opening the valve by acting on the valve-stem, as shown in Fig. 3.

Having thus described my invention, I claim as new and desire to secure by Letters Patent—

1. In an automatic fire-extinguisher, the combination, with the valve seat and valve, of the compound levers, substantially as described, constructed to be secured by a fusible solder to hold the valve to its seat, as described, and the fusible connection for securing said levers.

2. In an automatic fire-extinguisher, a system of compound levers arranged to hold the valve against the internal pressure, as described, and the fusible connection for securing said levers.

3. A valve constructed to control the fluid-supply to automatic fire-extinguishers, held to its seat by means of compound levers, which are secured by a fusible connection, as described.

4. The combination, with the outlet *a*, surrounded with a valve-seat, of the valve and deflector *b*, held to the seat by means of the levers *c* and *d*, the free end of the lever *d* being secured to the frame *g* by a fusible solder, as described.

FREDERICK GRINNELL.
